The ornamental design for a combined fishing pole alert and tackle box, as shown and described.

DESCRIPTION

FIG. 1 is a front perspective view of the combined fishing pole alert and tackle box showing my new design;

FIG. 2 is a rear perspective view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view with the tackle box closed;

FIG. 8 is a bottom plan view thereof; and,

FIG. 9 is a top plan view with the tackle box open.

The break-lines in the stake portion of the fishing pole alert device indicate indefinite length.

The pole position of claimed design has been broken away in FIGS. 1-6 to show indeterminate length.
